SUCTION CLEANER

Bernard C. Becker, Canton, Ohio, assignor to
 The Hoover Company, North Canton, Ohio, a
 corporation of Ohio

Application March 20, 1935, Serial No. 11,935

7 Claims.

(Cl. 15—9)

The present invention relates to suction cleaners in general and particularly to new and novel improvements in odorizer units in suction cleaners. More specifically the invention comprises a new and improved suction cleaner unit incorporating odor-creating means, the odor-creating means remaining operative, if desired, when the cleaner is used in combination with a dusting tool unit.

10 The odorizer unit in a suction cleaner performs a valuable function by disguising the dry dust smell caused by that very small percentage of foreign matter which is not removed from the air by the filtering medium of the cleaner. Odorizer units have heretofore been incorporated into a suction cleaner construction so that they operated in the use of the cleaner in on-the-floor cleaning. With the cleaner converted for off-the-floor cleaning, however, additional odor-20 creating means were necessary as the cleaning air in entering the cleaner no longer passed over the volatile element. By the present invention a construction has been provided in which the odorizer unit remains operative in both the on-25 the-floor cleaning and the off-the-floor cleaning relationships of the suction cleaner.

It is an object of the present invention to provide a new and improved suction cleaner. It is another object of the invention to provide new 30 and improved odor-creating means in a suction cleaner. A further object is the provision in a suction cleaner of an odorizer unit thru which air is drawn by the suction-creating means of the cleaner when the cleaner is used in on-the-35 floor cleaning and also when it is used in off-the-floor cleaning. Still another object is the provision, in a suction cleaner, of an odorizer unit which is interiorly connected to the eye of the suction-creating fan and fan chamber. A still 40 further object is the provision of a suction cleaning unit, including an odorizer unit, which is adapted to receive and cooperate with a dusting tool unit without affecting the operation of the odorizer unit. These and other more specific 45 objects will appear upon reading the following specification and claims and upon considering in connection therewith the attached drawing to which they relate.

50 Referring now to the drawing in which preferred embodiments of the present invention are disclosed:

55 Figure 1 is a side elevation of a modern suction cleaner incorporating the present invention; Figure 2 is a partial bottom view of the cleaner

shown in Figure 1 illustrating the position of the odorizer unit;

Figure 3 is a partial bottom view of the cleaner shown in Figure 1 with the dusting tool converter connected for off-the-floor use;

Figure 4 is a section through the cleaner upon the line 4—4 of Figure 2 with the machine related for on-the-floor use;

Figure 5 is a section upon the line 5—5 of Figure 3 in which the machine is related for off-the-10 floor use;

Figure 6 is a section upon the line 6—6 of Figure 3 showing the air passageway connecting the odorizer unit to the eye of the fan chamber;

Figure 7 is a section similar to Figure 5 thru 15 a modification in which the interior of the odorizer unit is connected into the eye of the fan chamber at a slightly different position;

Figure 8 is a view in perspective of a cage of volatile element adapted to be used in the present invention.

In the drawing a modern suction cleaner is disclosed. The cleaner nozzle 1 is interiorly connected through an air passageway 2, having a removable section 3, to the eye 4 of the fan chamber 5. Within the fan chamber 5 is a rotatable fan 6 which is carried upon the lower end of a motor shaft 7 and which functions, in the operation of the cleaner, to create a reduced pressure at the eye of the fan chamber which is also effective in the air passageway 2 and nozzle 1. This reduction of pressure causes a flow of air from the nozzle, thru the air passageway 2 and into fan chamber 5. From that chamber the air is exhausted, under the force of the fan 6, through the exhaust outlet 8 into the removable dust bag 9 removably secured thereto by suitable means. The motor casing 11 is positioned immediately above the fan chamber 5 and the motor proper, while not shown, is any common and well-known type adapted for suction cleaner usage. The cleaner body is movably supported by front and rear wheels 12 and 13, the latter preferably being provided with adjusting means 14 by which they may be adjusted relative to the body of the machine for the purpose of raising and lowering the nozzle 1. A handle 15 is pivoted at the sides of the fan chamber 5 and is provided with an arcuate sector 16, the outer surface of which is provided with suitable seats 17 which are adapted to cooperate with a spring-pressed detent 18 to position the handle.

With the cleaner in its on-the-floor cleaning relationship the nozzle 1 is connected directly to the fan chamber 5 through the air passage-

2,070,643

way 2 including the movable section 3. When it is desired to clean drapes, curtains, and similar articles positioned above the supporting surface the section 3 of the air passageway is removed from the cleaner, an operation requiring only the manual displacement of a detent 19 from its clamping position on the section 3. The dusting tool converter member 20 can then be positioned and secured directly to the fan chamber at its eye by the cooperation of the detent 19 there-with.

Converter member 20 comprises a central body portion which on its open side is of the same shape as the eye 4 of the fan chamber and is adapted to extend therein as far as permitted by a peripheral flange 21 formed upon its exterior. With the converter locked in place by the detent 19 the

air tight relationship of the fan chamber

and the converter member 20 is secured to the fan chamber.

With the converter member 20 secured to the fan chamber, the interior of the fan chamber is

in communication with the interior of the air passageway 51 which is in turn in communication with the exterior of the fan chamber.

With the converter member 20 secured to the fan chamber, the interior of the fan chamber is

in communication with the interior of the air passageway 51 which is in turn in communication with the exterior of the fan chamber.

With the converter member 20 secured to the fan chamber, the interior of the fan chamber is

in communication with the interior of the air passageway 51 which is in turn in communication with the exterior of the fan chamber.

With the converter member 20 secured to the fan chamber, the interior of the fan chamber is

in communication with the interior of the air passageway 51 which is in turn in communication with the exterior of the fan chamber.

With the converter member 20 secured to the fan chamber, the interior of the fan chamber is

in communication with the interior of the air passageway 51 which is in turn in communication with the exterior of the fan chamber.

cut-out sector 34 to accommodate the baffle or wall 28 in the housing. The height of cake 33 is such that, when it is positioned within housing 24, the port 29 is positioned thereabove. Air is adapted to be drawn into the housing through 5 the port 29, to travel across the top of cake 33 around the baffle 28 and to leave the housing through the air passageway 30, traveling to the eye fan of the fan chamber under the suction created by the suction-creating fan 10

To control the operation of the odorizer unit there is provided in one position, closes the pivotal 25 thru which air enters the housing 24, 10

which is carried by a pin 36 and connects to the valve 37 and either the valve 38 or

valve 39 which connects to the valve 37 and

of air through said odorizer housing and into said fan chamber.

4. In a suction cleaner, suction-creating means adapted to be connected to a floor nozzle or to a dusting tool unit, a volatile element container connected directly to said suction-creating means so as to be unaffected by the connection of said means to a floor nozzle or to a dusting tool unit, and means controlling the flow of volatilizing air thru said container.

5. In a suction cleaner, suction-creating means adapted to be connected to a floor nozzle or to a dusting tool unit, a volatile element container connected directly to said suction-creating means so as to be unaffected by the connection of said means to a floor nozzle or to a dusting tool unit, means connecting said container to atmosphere, and manually operable means controlling the flow of air into said container.

10 6. In a suction cleaner, suction-creating means adapted to be connected directly to a floor nozzle or directly to a dusting tool unit, a volatile element container connected directly to said suc-

tion-creating means so as to be unaffected by the connection of said means to a floor nozzle or to a dusting tool unit, an air port connecting said container to atmosphere, a manually operable pivoted valve adapted to close said port, and means cooperating with said valve to indicate to the operator the position of said valve.

15 7. In a suction cleaner, suction-creating means adapted to be connected directly to a floor nozzle or directly to a dusting tool unit, a volatile element container connected directly to said suction-creating means so as to be unaffected by the connection of said means to a floor nozzle or to a dusting tool unit, means connecting said container to atmosphere, a manually operable valve 15 including a handle adapted to control the flow of air thru said container, said handle being extended adjacent a stationary part of the body of said cleaner, and position indicating means on said stationary part cooperating with said handle 20 to indicate the position of said valve.

BERNARD C. BECKER.
